US00D853370S

(12) **United States Design Patent** (10) **Patent No.:** **US D853,370 S**
Matsuoka et al. (45) **Date of Patent:** **** Jul. 9, 2019**

(54) **PHONE**

(71) Applicant: **Google Inc.**, Mountain View, CA (US)

(72) Inventors: **Yoshimichi Matsuoka**, Sunnyvale, CA (US); **Alberto Villarreal Bello**, San Jose, CA (US); **Vincent Claudepierre**, San Francisco, CA (US); **Max Ken Yoshimoto**, Sunnyvale, CA (US); **Ji Hye Bae**, Mountain View, CA (US)

(73) Assignee: **Google LLC**, Mountain View, CA (US)

(**) Term: **15 Years**

(21) Appl. No.: **29/604,921**

(22) Filed: **May 22, 2017**

(51) LOC (11) Cl. **14-03**

(52) U.S. Cl.

USPC **D14/248**

(57) **CLAIM**

The ornamental design for a phone, as shown and described.

DESCRIPTION

FIG. 1 is a bottom, front, left perspective view of a phone showing our new design;

FIG. 2 is a top, rear, right perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is a top plan view thereof;

FIG. 8 is a bottom plan view thereof;

FIG. 9 is a partial enlarged bottom plan view; and FIG. 10 is a partial enlarged top, front, left perspective view; and,

FIG. 11 is a partial enlarged bottom, front, right perspective view.

The broken lines of uneven length, which correspond to the edge of a portion of the phone, define the bounds of the claim and form no part of the claimed design. The portions of the phone depicted in broken lines of even length form no part of the claimed design.

1 Claim, 11 Drawing Sheets
